UNITED STATES PATENT OFFICE.

SALVATORE COLLEDANCHISE, OF BOSTON, MASSACHUSETTS.

FLEXIBLE TOY.

Application filed November 10, 1928. Serial No. 318,321.

This invention relates to a flexible toy simulating a snake, or other living thing, and adapted to be manipulated so as to wriggle or undulate like a snake, the toy including an elongated body composed of a flexible connecting strip extending from end to end of the body, and body blocks fixed in pairs to opposite sides of the strip and having oppositely facing ends forming transverse grooves in opposite sides of the body, whereby lateral flexure of the body is permitted.

A toy thus constructed is well known, but, in consequence of the grooves extending across the opposite sides of the body, does not present a sufficiently realistic appearance. In other words, its surface is deeply indented and does not closely resemble the smooth surface provided by the skin of a snake or a fish.

The object of the invention is to provide a flexible toy including a body characterized as above stated, and a flexible sheath covering the blocks and concealing the transverse grooves when the body is straight, so that the sheath simulates a practically continuous skin, the sheath being adapted to be flexed with the body, and to partially conceal the grooves in the bulging side of the flexed body, and entirely conceal the grooves in the opposite side, so that the snake-like effect of the body is not detracted from by the grooves to an objectionable extent, the grooves at the bulging side being nearly concealed, while those in the opposite side are entirely concealed.

Of the accompanying drawings forming a part of this specification,—

Figure 1 is a side view of a toy embodying the invention.

Figure 2 is a fragmentary side view on an enlarged scale, a portion of the sheath being shown in section.

Figure 3 is a section on line 3—3 of Figures 1 and 2.

Figure 4 is a section on line 4—4 of Figures 1 and 2.

Figure 5 is a view similar to Figure 3, showing a result of flexure of the body and sheath.

Figure 6 is a fragmentary perspective view, showing a portion of the flexible strip and two pairs of body blocks attached thereto.

Figure 7 is a fragmentary perspective view, showing a portion of the sheath.

The same reference characters indicate the same parts in all of the figures.

The flexible body of the toy is composed of an elongated flexible connecting strip 12, preferably of cloth, and body blocks 13, fixed in pairs to opposite sides of the strip, each block being preferably molded from a plastic composition which adheres to the strip and is adapted to be solidified by drying. The blocks have oppositely facing ends, forming transverse V-shaped grooves 14 in opposite sides of the body.

As here shown, the body is formed to simulate a snake. It may be formed to simulate a fish, as shown by my Patent No. 1,636,589, dated July 19, 1927.

15 designates a flexible sheath covering the blocks 13, and bridging the grooves 14. The sheath may be cemented, or otherwise secured to the blocks, and may be composed of an elastic rubber tube, normally of a diameter to fit the tapering end portions of the body, and adapted to be stretched to fit the larger midlength portion of the body. 80 If desired, the sheath may be formed by wrapping a blank of any suitable sheet material around the body and causing one edge of the blank to overlap the other, as indicated at 16 in Figure 7. Slits 17 are cut in the portions of the sheath which bridge the grooves 14, the slits extending lengthwise of the grooves and permitting flexure of the sheath with the body.

When the body is flexed the slits at the bulging side of the body are opened and those at the opposite side are closed, as shown by Figure 5. When the body is straight, all of the slits are closed, as indicated by Figures 1, 2 and 3, so that the sheath simulates a practically continuous skin concealing the grooves 14. The opening of the slits at the bulging side of the body is relatively slight, the notches formed by the opening of the slits being much narrower than the notches 14, so that the notches 14 at the bulging side are inconspicuous, and those at the opposite side are concealed.

The body may be provided at one end with a head 22, and at the opposite end with a tail, the head projecting from one end of the sheath, and the tail being covered by the sheath.

I claim:

A jointed toy comprising a flexible body composed of an elongated flexible connecting strip, and body blocks fixed in pairs to op-

posite sides of the strip, and having oppositely facing ends forming transverse V-shaped grooves in opposite sides of the body, whereby lateral flexure of the body is permitted, the toy being characterized by a flexible sheath covering the blocks and bridging said grooves, the bridging portions of the sheath having slits permitting flexure of the sheath with the body, all the slits being

closed when the body is straight, so that the 10
sheath simulates a practically continuous
skin concealing the grooves, the slits at the
bulging sides of the body opening but slight-
ly when the body is flexed.

In testimony whereof I have affixed my 15
signature.

SALVATORE COLLEDANCHISE.
